REED OPERATED MUSICAL INSTRUMENT

Charles E. Wetzler, Long Island City, N. Y.

Application July 13, 1948, Serial No. 38,533

2 Claims. (Cl. 84—377)

1

This invention relates to musical instruments of the reed type such as harmonicas and the like.

It has as a purpose a novel and improved reed operated musical instrument having substantially improved tonal quality, increased loudness range and more efficient conversion of air pressure to sound energy.

Another object is a new and improved musical instrument of the reed operated type wherein the reed sensitivity to air pressure and response to variations in pressure is greatly improved.

Another object of the invention is a novel and improved harmonica.

For a better understanding of these and other objects and advantages of the invention reference is made to the following description and accompanying drawings forming part of this application.

In the drawings—

Fig. 1 is a partially sectional perspective view of a reed-operated musical instrument showing, in general, an embodiment of the invention;

Fig. 2 is a partial, sectional view of one element showing details of one embodiment of the invention;

Fig. 3, A, B, illustrate, in a more diagrammatic way, other embodiments of the invention.

Fig. 4 is a partially sectional view of another detail of an instrument embodying the invention.

Reed operated musical instruments such as harmonicas and the like generally consist of a flat body portion having a series of channels formed in each side thereof to act as air ducts or chambers for the operation of the reeds. The reeds are mounted on slotted plates which are placed on each side of the body portion with each reed in alignment with one of the chambers. Although it is customary to construct a harmonica with all of the blow reeds on one side of the body and the draw reeds on the other, instruments are also made with both blow and draw reeds mounted on a single plate. In this instance the body part may be provided with chambers only on one side with individual chambers communicating with the blow and draw reeds.

I have found that with the conventional instruments numerous air pockets exist with the result that substantial turbulence and eddy currents are produced which materially reduce the efficiency of the instrument, as for example in instruments having generally rectangular chambers. In conventional instruments therefore,

2

because of a relatively low efficiency and large power loss, large volumes of air are required for actuation of the reeds. This greatly limits the loudness range obtainable on the instrument.

Under these conditions the reed is frequently forced or overdriven by the air so that instead of operating at its resonant frequency it operates at some slightly lower frequency with a substantial increase in harmonic content. The note thus produced sounds flat and the increased harmonic content gives the note a distorted and strained tone. Moreover, with the conventional instrument musical accompaniment is difficult because of the sluggish response and lack of sensitivity of the instrument to changes in air pressure. The player rapidly becomes fatigued because of the large volumes of air required and as a result proper interpretation of the music can not be attained.

With my novel and improved chamber construction I have been able to substantially eliminate all air pockets and their attendant power losses and provide a streamlined path for the air to and from the reeds thus matching the physical dimensions of the chamber aerodynamically with the characteristics of the particular reed served by that chamber. In this way the air economy is greatly improved since it is possible to operate the instrument with very much smaller volumes of air and with considerably improved tonal quality and materially increased loudness range. I have attained an improved operation by increasing the velocity of the air stream, in the case of a blow reed for instance, from the mouth of the chamber to the reed with the result that a substantially uniform direct stream of air impinges on and actuates the reed at its normal resonant frequency. The amplitude can then be readily varied throughout a relatively wide range without overdriving the reed and modifying the fundamental frequency or normal harmonic content of the note.

Moreover, by reason of the increase in efficiency of the instrument I have found that it responds almost instantly to very slight air pressures.

As previously mentioned, musical instruments of this type are formed with a plurality of single open ended chambers for the draw and blow reeds. In conventional practice as I know it, the chambers are substantially rectangular in cross section with one of the side walls formed by the reed plate so that a vibrating reed constitutes part of the chamber wall. The player then either blows or draws on the open end of the

chamber, depending on whether the reed is of the blow or draw type, to actuate and vibrate the reed to produce a musical tone.

Fig. 2 illustrates one of my novel and improved chambers formed in the harmonica body 10. It is provided with tapered side walls 12. In this way air entering the open end of the chamber at a substantially constant pressure, as obtained for instance by the blowing of a player, will increase in velocity during its travel through the tapered part 12. The high velocity air then strikes or impinges on the blow reed 18 and causes it to vibrate. This increased air velocity causes the reed to respond more rapidly and easily, enabling the player to more accurately control the amplitude of oscillation of the reed with a corresponding improvement in tonal quality by avoidance of overdriving or forcing the reed by larger volumes of air.

In some instances, especially where short chambers are used as in the case of the higher frequency reeds, it may be desirable to have a relatively large change in area from one end of the chamber to the other.

In Fig. 2 both the side walls 12 and the bottom 13 are tapered toward the closed end 14 of the chamber so that the cross-sectional area decreases uniformly from the open to the closed end. In Figs. 3A and 3B the area of the chamber throughout its length varies at a predetermined rate of change.

Fig. 3A illustrates a harmonica body part 40 having a chamber 50 in which both the walls 51 and the bottom 52 converge inwardly from the mouth at a constantly increasing rate so that the acceleration of the air will be progressively increased as it proceeds through the chamber. In Fig. 3B I have again shown the body part 40 of a harmonica having curved walls 53 and a curved bottom part 54. In this embodiment, however, the walls and bottom part have a convex configuration so that the rate of acceleration of the air is greatest at the mouth and decreases as it proceeds through the chamber.

In the construction of my harmonica it may be desirable to use combinations of two or more of the new and improved chambers I have illustrated in Figs. 2 and 3 so that the resultant instrument will require substantially uniform air pressure for the reproduction of the various tones. For instance, it may be desirable to use a chamber as illustrated in Fig. 3B for actuating a very high frequency reed so that a maximum air velocity can be attained in a relatively short length, whereas it may be desirable to use a chamber of the character illustrated in Fig. 2 for a lower frequency reed which is physically longer than a higher frequency reed and therefore enables the use of a longer chamber which will permit the attainment of substantially equivalent air velocities with a smaller degree of convergence from the mouth of the chamber to the inner end thereof.

For the purpose of clearly disclosing some of the features of this invention I have illustrated the chamber in Fig. 3 as having a substantially rectangular section. I have found, however, that eddy currents and turbulence which increase the friction of an air passage and lower the efficiency of the system can be materially reduced in a harmonica chamber by providing chambers having curved sections and I have illustrated an embodiment thereof in Figs. 1 and 2 inclusive.

With the embodiments or combinations of the embodiments in Figs. 2 and 3. I have found, in

the case of a mouth-operated harmonica, a loudness range from pianissimo to fortissimo can be obtained by the ordinary player not obtainable with conventional harmonicas with which I am familiar. Because of the decrease in both volume and pressure of air required to start the individual reeds to vibrate, the player is able to render more accurate control over the applied air pressure and the reeds can be vibrated in their normal manner to produce a tone of high quality. In conventional harmonicas where the power losses are high, the operator or player must necessarily produce relatively large volumes of air at high pressure in order to start the reeds to vibrate, and this condition results in an actual forcing of the reeds so that instead of oscillating at their true resonant frequencies, will oscillate at different fundamental frequencies and produce a large distorted harmonica content. The resultant tone appears to the ear to be out of pitch and the several reeds when forced in this way go out of pitch non-uniformly.

My invention permits a wide variation in musical interpretation and exploitation not otherwise feasible and enables the employment of faster tempos in harmonica music.

In addition to the new and improved chamber designs described in Figs. 2 and 3, still further improvements in operation can be attained by mounting the reed relative to the chamber so that the resistance to the air flow will be relatively low in comparison to the reactance of the reed. In other words, by the elimination of unnecessary air pockets between the reed and the chamber it is possible to substantially raise the Q of the reed so that the power required to sustain oscillation is substantially decreased. In Fig. 4 I have illustrated an embodiment of this feature in connection with a draw reed of a mouth operated harmonica.

Referring to Fig. 4, 70 represents a harmonica body having a chamber 71 therein of the type illustrated in Fig. 2 wherein the bottom wall 72 tapers upwardly toward the rear end of the chamber. Closing the top of the chamber 71 is the reed plate 74 having a reed 75 mounted on the plate 74 and adapted to vibrate within a slot 76. The direction of vibration of the reed is illustrated by the arrow *a* and the extent of such vibration in a downward direction is indicated by the broken outline of the reed.

I have been able to further improve the efficiency of harmonicas by proportioning the chamber relative to the reed so that air pockets are substantially eliminated. This greatly decreases turbulence and eddy currents that in effect reduce the Q or the efficiency of the instrument. I have accomplished this by terminating the chamber 71 at a point in front of the inner end of the reed slot 76 and making the clearance 77 between the reed 75 and the upper face 81 of the body 70 just large enough to accommodate the swing of the reed 75 when it is vibrated. With this structure I am able to obtain a maximum conversion of the energy of the moving column of air into sound energy.

In Fig. 4 I have illustrated a chamber 71 in the body part 70 having converging walls 73.

In Fig. 2 I have illustrated my new and improved method of improving the Q or the efficiency of a system having a musical reed such as a blow reed in a mouth-operated harmonica having upper and lower sections.

In Fig. 2 I have denoted the body part of the harmonica by the numeral 10 having upper and

lower chambers 11 and 11a. For the purposes of this description I have illustrated but a single reed plate 15 having a blow reed 18 mounted therein for vibration within the slot 16. In conventional practice as I know it, the inner wall 17, of the chamber 11 is usually terminated at a point beyond the free end of the reed 18 so that the air pocket would be formed between the rear end of the chamber and the upper plate 15. Moreover, in conventional practice the chambers are made substantially rectangular in cross-section and the relatively sharp corners produced additional eddy currents and other losses. With my invention I terminate the rear wall 17 of the chamber 11 substantially in line with the end of the slot 16 so that all of the air entering the mouth of the chamber will be directed upwardly at the reed and be converted into sound energy. Moreover, the particular chamber 11 is provided with a curved rear wall 17 to provide a smooth path for the air.

Referring to Fig. 1 showing a single plate harmonica embodying my invention, 110 denotes the harmonica body having a reed plate 112 and a reed plate cover 114. The body part 110 is provided with a plurality of blow reed chambers 116 and interposed draw reed chambers 118. These blow and draw reed chambers embody the new and improved designs which I have illustrated in Figs. 2 to 4 inclusive. Each successive pair of blow and draw reed chambers 116 and 118 respectively is arranged to terminate in a single opening or chamber mouth 120 since in the operation of the harmonica draw and blow reeds are obviously not operated simultaneously. The reed plate is constructed to conform with the chambers in the body 110; that is, the blow reeds 122 and the draw reeds 124 are mounted alternately to cooperate with their respective chambers in the body 110. The cover plate 114 in this particular embodiment is generally streamlined and tapering inwardly toward the reeds.

In certain instances my new and improved harmonica may be provided with chambers having a curved rear wall substantially as illustrated at 14 in Fig. 2. This feature obviously may be embodied in any of the improved chambers shown. Moreover, although I have shown individual upper and lower chambers for two plate harmonicas certain advantages of my invention may also be realized by using a single chamber for opposing upper and lower reeds. In this instance, the side and end walls of the chambers are shaped according to the invention and the chambers are completed by closing one side of the chamber with a plate having a draw reed mounted thereon and closing the other side of the chamber with a blow reed mounted thereon.

From the foregoing description of my invention it is clear that a reed operated musical instrument embodying my invention provides in effect a complete streamlined path for the air from the point of entrance to the point of exit from the chambers. By reducing turbulence in the air stream and the elimination of air pockets to produce the smooth flow of the air through the chambers, the ease of operation and rapidity of response of the instrument are improved. The tonal quality is also improved and the range

of loudness and tempos are substantially increased. Moreover, by means of tapering the chambers, as I have described, I can materially increase the velocity of the air striking the reed and obtain a more efficient conversion of air pressure to sound energy and more uniform operation of the instrument over the entire tonal range. Moreover, I have found that instruments constructed in accordance with my invention will stay in tune for a longer period of time because, among other reasons, the reeds are not forced but are free to vibrate in their natural periods. The overall response of the instrument is more uniform, sensitive, and easily controlled. All these and other advantages combine to greatly improve the rendition of musical compositions.

I claim:

1. A reed operated musical instrument, comprising a body having pairs of coordinated blow and draw chambers open at its front, reeds mounted each in a slot to swing therein and to cooperate with one of said chambers, the reed associated with a blow chamber mounted with its free end toward the rear of the body and the reed associated with a draw chamber mounted with its free end toward the front of the body, the blow chamber of each pair being longer than the draw chamber, said chambers tapering in cross section inwardly from the front edge so as to cause a variation of air velocity in the particular chamber and a maximum velocity substantially at the swinging free end of the particular reed, the length and the variation of cross section of each individual chamber being aerodynamically matched with the characteristics of the particular reed served by the respective chamber.
2. A reed operated musical instrument as specified in claim 1, the variation of cross section in an individual chamber being not uniform along its length, the rate of variation being aerodynamically matched with the characteristics of the particular reed associated with the respective chamber.
